CLAIM

The ornamental design for a display screen with icon, as shown and described.

DESCRIPTION

FIG. 1 is a front view of a display screen with icon showing the new design;

FIG. 2 is a front view of a display screen with icon showing an alternative embodiment of the new design; and,

FIG. 3 is a front view of the display screen with icon of FIG. 1, showing the icon in smaller scale on a display screen. The broken line showing the display screen forms no part of the claimed design. The dot-dash broken line in FIG. 3 forms no part of the claimed design.

1 Claim, 3 Drawing Sheets
